UNITED STATES PATENT OFFICE

ERIC J. HIRVONEN, OF WORCESTER, MASSACHUSETTS

DESIGN FOR A VALVE CASING

Application filed September 1, 1931. Serial No. 40,973. Term of patent 7 years.

To all whom it may concern:

Be it known that I, ERIC J. HIRVONEN, a citizen of the United States, residing in Worcester, in the county of Worcester and State of Massachusetts, have invented a new, original, and ornamental Design for Valve Casings, of which the following is a specification, reference being had to the accompanying drawing, forming part thereof.

The figure is a plan view of a valve casing, showing my new design.

The body portion of the valve casing is hexagonal in cross-section.

I claim:

The ornamental design for a valve casing, as shown and described.

ERIC J. HIRVONEN.
